UNITED STATES PATENT OFFICE.

WESLEY J. CORBETT, OF DETROIT, MICHIGAN.

SHADOWGRAPH-MACHINE.

1,099,023.

Specification of Letters Patent.

Patented June 2, 1914.

Application filed July 24, 1913. Serial No. 731,045.

To all whom it may concern:

Be it known that I, WESLEY J. CORBETT, a citizen of the United States, residing at Detroit, in the county of Wayne and State of Michigan, have invented certain new and useful Improvements in Shadowgraph-Machines; and I do hereby declare the following to be a full, clear, and exact description of the invention, such as will enable others skilled in the art to which it appertains to make and use the same.

This invention comprehends improvements in shadowgraph machines and relates more particularly to a machine whereby a shadow may be projected upon a screen or other surface and moved so as to produce a moving picture.

One of the objects of the invention is to provide a machine of this nature which shall be of simple construction, easy to operate, and very practical.

Another and more specific object of the invention resides in the provision of a shadowgraph including a supporting structure, a movable web or film having opaque portions which form shadows representing different scenes and objects, and means for winding said web from one roll to another.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a front elevation of my machine, Fig. 2 is an end elevation, Fig. 3 is a rear elevation of my machine, Fig. 4 is a section taken on the plane of line 4—4 of Fig. 3, Fig. 5 is a section taken on the plane of line 5—5 of Fig. 3, and, Fig. 6 is a detail perspective view of one part of the machine to be hereinafter described.

Referring in detail to the drawings by numerals, 6 designates, generally, a supporting structure or table having a top 7 of rectangular shape, to the under side of which adjacent the ends thereof are secured the cross pieces 8. The shelves or supports 9 and 10 are secured to the rear edges of the top 7 by means of the vertical members 11, and are disposed in a horizontal plane below the surface of the top. These shelves are

comparatively short and extend a slight distance around the ends of the top 7. Legs 12 connected by the cross bars 13, support the top and shelves and are braced by the struts 14. A frame comprising four uprights 15 connected at their upper ends by the longitudinal bars 16 and cross bars 17, is supported upon the table above the same.

Rolls or spools 18 and 19 are provided having trunnions 20 formed upon their upper ends which extend through openings 21 formed in the cross bars 17 of the frame. The lower ends of the rolls are supported upon shafts 22 and 23, which have squared upper ends, as indicated by the numeral 24 for reception within sockets formed in the bottoms of the rolls. These shafts extend into openings formed in the shelves 9 and 10 and carry collars 25 which limit their downward movement. The shaft 24 carries rigidly secured thereto a ratchet wheel 26, which is engaged by a spring pawl or brake 27 secured to the block 28. A bevel gear 29 is rigidly secured to the shaft 23 and meshes 30 with a bevel gear 30 formed upon one end of a shaft 31, which extends through a bearing 32 mounted upon the shelf 10. A crank handle 33 is secured to the other end of the shaft 31 whereby the latter may be rotated 35 so as to cause the web 34 to wind upon the spool or roll 19. This web or film is formed of some transparent material and carries opaque sections which form shadows when the light is positioned behind the web. If 40 desired, slides may be used in place of the film or web.

In operation the machine is stationed behind a cloth screen and a light placed so as to shine against the web and throw 45 shadows upon the screen. By rotating the spools so as to cause the web to wind upon one of them, the shadows will move across the screen and give the appearance of a moving picture. The rolls may be easily 50 detached from the frame by raising them slightly so as to disconnect their lower ends from the shafts 22 and 23. If desired, the table and frame may be made so as to fold 55 into a compact form to facilitate transportation.

In order that slides may be conveniently used in connection with the web 34, or in place thereof, I provide the table top with a longitudinal slot 35, shown by the dotted 60 lines in Fig. 2.

From the foregoing description taken in

connection with the accompanying drawings, it will be apparent that I have provided a simple, practical, and cheaply manufactured shadowgraph machine which may be operated so as to furnish amusement for many spectators.

It is to be understood that while I have shown and described the preferred embodiment of my invention, I do not wish to be limited to this exact construction, combination, and arrangement of parts, but may make such changes as will fall within the spirit and scope of the invention as claimed.

Having thus described my invention, I claim:

1. In a machine of the character described, a supporting structure, a skeleton frame formed above the same, a pair of spools having trunnions formed upon their upper ends and sockets formed in their lower ends, said sockets being received within openings formed in said frame, a pair of revoluble shafts journaled in the supporting structure, and extending into the sockets formed in said spools, a web connected to the spools and adapted to be wound from one to the other, said web being transparent and formed with opaque portions, and means for rotating the spools.
2. In a machine of the character described, a table, shelves secured to the rear edge of the table top, and disposed in a plane below the same, a frame work supported above the table, a pair of spools having trunnions formed upon their upper ends, the frame work being formed with openings to receive said trunnions, a pair of shafts having their upper ends squared,

the lower ends of the spools being formed with sockets to receive said squared portions of the shafts, the shafts being journaled vertically in openings formed in the shelves, a bevel gear rigidly secured to one of said shafts, a third shaft having a bevel gear secured thereto and meshing with said first mentioned gear, means for rotating the last mentioned shaft, and a web secured at its ends to said spools.

3. In a machine of the character described, a table having a top disposed in a horizontal plane, shelves secured to the rear edge of said top and disposed in a plane below the same, a frame work supported above the table, a pair of vertical spools having trunnions formed upon their upper ends and squared sections in their lower ends, a frame work being formed with openings to receive said trunnions, a pair of vertical shafts journaled within openings formed within said shelves, the shafts being formed with squared upper ends for reception within said sockets, means for retarding the rotation of one of the shafts, a bevel gear secured to the other shafts, a third shaft, a bevel gear rigid with the third shaft and meshing with the bevel gear, means for revolving the last mentioned shaft, and a web adapted to be wound from one spool to the other, said web being transparent and formed with opaque portions.

In testimony whereof I affix my signature in presence of two witnesses.

WESLEY J. CORBETT.
